UNITED STATES PATENT OFFICE.

WILLIAM C. STEVENS, OF AKRON, OHIO, ASSIGNOR TO THE FIRESTONE TIRE & RUBBER COMPANY, OF AKRON, OHIO, A CORPORATION OF OHIO.

TIRE-FLAP-MAKING MACHINE.

1,169,204.

Specification of Letters Patent. Patented Jan. 25, 1916.

Application filed July 31, 1913. Serial No. 782,175.

To all whom it may concern:

Be it known that I, WILLIAM C. STEVENS, a citizen of the United States, residing at Akron, in the county of Summit and State of Ohio, have invented certain new and useful Improvements in Tire-Flap-Making Machines, of which the following is a specification.

In pneumatic tires consisting of an outer casing and an inner tube it is usual to provide a flap which overlaps the gap between the two edges of the casing to form a smooth bearing for the inner tube and to prevent the same catching beneath and being pinched by the casing. This flap, although commonly formed of material other than the material of the casing, is sometimes connected along one edge to the edge of the casing while the other edge of the flap is left free. The flap is ordinarily composed of laminations, each succeeding layer of fabric being slightly narrower than the one beneath whereby it is rendered thicker along the center than at the edges and is moreover preferably cupped transversely to conform to the contour of the casing and tube with which it associated in use.

The object of the invention is the provision of a simple and efficient apparatus for the manufacture of flap stock.

A preferred embodiment of the invention is set forth in the accompanying drawings and in the description based thereon. As, however, the invention is capable of embodiment in other and varied constructional forms the drawings and description are to be taken in an illustrative rather than in an unnecessarily limiting sense.

In the drawings—Figure 1 is a side elevation of a preferred form of the machine; Fig. 2 is a top plan view; Fig. 3 is an enlarged detail showing two sets of applying rolls and supply drum; Fig. 4 is a longitudinal sectional view of the dusting device; Fig. 5 is a transverse section on the line 5—5 of Fig. 1; Fig. 6 is a similar section on the line 6—6 of Fig. 1; and Fig. 7 is a fragmentary view of the product.

The machine comprises generally speaking, a pair of longitudinal members 11, 11 suitably tied together at intervals in spaced relation and supported by the uprights 12,

12 and the braces 13. At intervals longitudinally of the machine are mounted in pairs standards 14, 15, 16, 17, 18 and 19, 55 serving respectively to support arms and bearings for the frictioned fabric supply spools 20, 21, 22, 23, 24 and 25 respectively while below the machine frame at the rear end is journaled a supply spool 26. In the lower portion of the several pairs of standards are journaled feed rolls 27, 28, 29, 30, and 31 while above the feed rolls are mounted in spring pressed bearings pressure rolls 32, 33, 34, 35 and 36. In advance of the standards 19 is suitably journaled another set comprising a feed roll 37 and a pressure roll 38. A drive sprocket 39 is loosely mounted upon the shaft of the feed roll 37 and is connected by means of the chain 40 with a sprocket 41 upon the shaft 42 which latter is driven by means of the pulley 43 and the belt 44 from a motor 45 or other suitable source of power. Upon the shaft 46 of the feed roll 37 is keyed a, 75 smaller sprocket 47, and upon the shaft of each of the feed rolls 28, 29, 30 and 31 is mounted a pair of sprockets 48 and upon the shaft of the feed roll 27 a single sprocket 48, these several sprockets are interconnected by means of sprocket chains 49, 49, whereby the several feed rolls are uniformly driven from the motor 45.

Upon the shafts of the feed rolls 27 and 37 are likewise mounted hand wheels 50 and 85 51 by means of which the feed rolls may be turned in either direction when desired. Yet in advance of the feed and pressure rolls 37, 38 is mounted a box 52 having a 90 hopper-shaped bottom 53 adapted to contain a quantity of talc or soap stone 54. This box has journaled in its side walls a dusting wheel 55 which has upon its periphery a series of flexible vanes 56 each composed of felt or similar fabric secured to the wheel by tacks 57, 57 or other suitable means. The shaft 58 of the dusting wheel carries a pulley 59 connected by the cross belt 60 with the hub 61 of the drive sprocket 39.

In advance of the dusting box 52 is mounted a tension device comprising three idler rolls 62, 63, 64 intergeared by means of tooth pinions 65, 66, 67, the middle roll

having mounted upon the shaft a friction drum 68 traversed by a friction brake 69 carrying an adjustable weight 70.

5 A take-up drum 71 is carried by spider arms 72 upon the shaft 73 driven by means of the pinions 74 and 75 and the pulley 76 and belt 77 from the pulley 78 on the shaft 46 of the drive roll 37. The belt 77 is advantageously provided with a belt tightener 79.

10 Upon the supply spool 26 is wound a strip of fabric 80 of a width corresponding to the greatest width of the flap to be produced, and upon the supply spools 20, 21, 22, 15 23, and 24, are wound strips of fabric respectively decreasing in width, the spool 25 carrying a fabric strip slightly less in width than the bottom layer 80 of the finished flap. The fabric strips from the spools 26,

20 20, 21, 22, 23, 24 and 25 are designated in Figs. 1 and 7 of the drawing as 80, 81, 82, 83, 84, 85 and 86 respectively. It will be observed that the strip of fabric 80 with the strip 81 superposed thereon is introduced between the first feed roll 27 and its pressure roll 32 whereby the two are brought into intimate pressure contact and caused to adhere one to the other. The resultant duplex strip with the strip 82 superposed

25 30 thereon is then introduced between the feed roll 28 and its pressure roll 33, and so on the laminated product from one set of feed and pressure rolls is introduced to the next set with another strip from the succeeding supply spool superposed in proper relation until the set of rolls 37, 38 are passed when the resultant strip 87 made up of many layers passes through the dusting box 52 above the dusting wheel 55, the soap stone 40 or talc being thrown by the vanes 56 upon the lower face of the strip.

The strip is led above the tension roll 65, below the tension roll 66, and above the tension roll 67, and then through a delivery 45 shoe or guide 88, the up-turned edges of which engage the outside of a take-up or cupping drum 71, and center it on the drum. The take-up drum is formed with a peripheral groove or channel 89, which is narrower 50 than the width of the flap under construction, and comprises a concave bottom, and straight parallel wings. It will be seen that as the flap stock passes through the guide 88, its edges meet the wings of the take-up 55 drum, and as the flap is being drawn under tension from the rolls 62, 63 and 64 by the slightly faster movement of the drum, and because of the concave shape of the bottom of the drum, it will assume the desired transverse curvature, which is fixed by curing.

In order to properly center each fabric supply spool there are mounted above the respective sets of feed and pressure rolls arms 90 carrying bearing rods 91 for the 60 supply spools, the rods 91 having thereon

adjustable side stops 92, 92 which retain the spool in proper position.

Mounted on the front face of each pair of standards and extending across the path of the fabric entering between the feed and presser rolls are three rods 93, 94, and 95, the lower strip or strips of adhering fabric passing between the rods 93 and 94 and the strip from the supply spool to be superposed thereon passing between rods 94 and 95. 70 The rods 93 and 95 each carry a pair of spaced gage stops or fingers 96, the function of these gage stops being to center each superposed strip and the underlying strips with reference to each other as they enter 80 between the succeeding feed and pressure rolls.

In order to drive the take-up drum independently of the feed and pressure rolls, whereby to wind a suitable cloth wrapping 85 about the completed flap thereon preparatory to curing, the drive sprocket 39, its hub 61 and the pulley 78 are locked together or formed integral and are loosely mounted on the shaft 46, and a suitable clutch, indicated 90 generally at 97, is provided whereby these members may at will be connected to or disconnected from the shaft 46 to which the sprocket 47 is keyed.

Each of the feed rolls 28, 29, 30, 31 and 37 is of very slightly greater diameter than the preceding roll whereby the peripheral speed of each roll is slightly greater than that of its predecessor and the peripheral speed of the take-up drum 71 is also slightly 100 greater than the peripheral speed of the last feed roll 37. In this way it is provided that the flat strip as it proceeds through the machine is subjected to stretching and is held taut, and as it is finally wound upon the take-up drum it is by its own tension compactly wound upon the drum and caused to conform to the concave contour of the groove.

When the supply from any spool is exhausted the machine will be stopped and a new spool placed in position. If by chance the exhaustion of the supply from any spool is not noticed until the rear end has passed through the next set of rolls the hand wheels 50 and 51 provide means whereby, the machine having been stopped, all of the feed rolls may in unison be given a reverse movement and the fabric caused to retrace its course until that portion of the flap having the interrupted layer is brought back to a position where the forward end from a new spool may be inserted. Upon such reverse movement of the machine it is obvious that the difference in peripheral speed of the feed rolls will cause a slackness in the strip between the several rolls, this slackness being again taken up when the forward motion of the machine is resumed. If found desirable the last supply spool 25 may con- 110 115 120 125 130

tain a strip of fabric wider than those immediately preceding and of substantially the same width as the bottom strip supplied by the spool 26 so that the resultant flap 5 will have a smooth upper as well as lower surface; but, preferably, the upper strip 86 of fabric is made slightly less than the bottom strip 80 so that a narrow margin of but one thickness of fabric is secured as indicated in Fig. 7.

I claim:

1. In a machine of the character described, the combination of a series of supply spools carrying fabric, a series of sets 15 of feed and pressure rolls arranged to receive adhering strips of fabric from the preceding rolls and a superposed strip of fabric from a supply spool, and a take-up drum having a grooved periphery of less 20 width than the flap, whereby to cup the latter, and means to drive the feed rolls and drum, substantially as described.
2. In a machine of the character described, the combination of a series of supply spools carrying fabric, a series of sets 25 of feed and pressure rolls each arranged to receive adhering strips of fabric from the preceding rolls and a strip of superposed fabric from a supply spool, means to drive 30 the successive rolls at a progressively increasing peripheral speed, a take-up drum having a grooved periphery of less width than the flap whereby to cup the latter, and means to drive the drum at a peripheral speed in excess of that 35 of the last feed roll, substantially as described.
3. In a machine of the character described, the combination of a series of supply spools carrying fabric of progressively 40 decreasing width, a series of sets of feed and pressure rolls arranged to receive adhering strips of fabric from the preceding rolls and a strip of superposed fabric from a supply spool, successive rolls having a 45 progressively greater diameter, means to drive the successive rolls in unison, a take-up drum having a grooved periphery of less width than the flap whereby to cup the latter, and means to drive the drum at a 50 peripheral speed in excess of that of the last feed roll, substantially as described.
4. In a machine of the character described, the combination of a series of supply spools carrying fabric, a series of sets 55 of feed and pressure rolls arranged to receive adhering strips of fabric from the preceding rolls and a superposed strip of fabric from a supply spool, a dusting box traversed by the flap, means therein to apply 60 the contents of the box to the flap, and a take-up drum having a grooved periphery of less width than the flap whereby to cup the latter, and means to drive the feed rolls and drum, substantially as described.
5. In a machine of the character de- 65
- scribed, the combination of a series of supply spools carrying fabric, a series of sets of feed and pressure rolls arranged to receive adhering strips of fabric from the preceding 70 rolls and a superposed strip of fabric from a supply spool, a dusting box traversed by the flap, a vane wheel therein to throw the contents of the box upon the flap, and a take-up drum having a grooved periphery of less width than the flap whereby to cup the latter, and means to drive the feed rolls and drum, substantially as described.
6. In a machine of the character described, the combination of a series of supply spools carrying fabric, a series of sets 80 of feed and pressure rolls each arranged to receive adhering strips of fabric from the preceding rolls and a strip of superposed fabric from a supply spool, means to drive 85 the successive rolls at a progressively increasing peripheral speed, a dusting box traversed by the flap, a vane wheel therein to throw the contents of the box upon the flap, a take-up drum having a grooved periphery of less width than the flap whereby to cup the latter, and means to drive the drum at a peripheral speed in excess of that 90 of the last feed roll, substantially as described.
7. In a machine of the character described, the combination of a series of supply spools carrying fabric, a series of sets 95 of feed and pressure rolls each arranged to receive adhering strips of fabric from the preceding rolls and a strip of superposed fabric from a supply spool, means to drive 100 the successive rolls at a progressively increasing peripheral speed, means to reverse the direction of rotation of the rolls, a dusting box traversed by the flap, rotary means therein to apply the contents of the box to the flap, tension rolls traversed by the flap, a take-up drum having a grooved periphery of less width than the flap whereby to cup the latter, and means to drive the drum at a peripheral speed in excess of that of the last feed roll, substantially as described.
8. In a machine of the character described, the combination of a series of supply rolls carrying fabric, a series of sets 105 of feed and pressure rolls arranged to receive adhering strips of fabric from the preceding rolls and a superposed strip of fabric from a supply spool, and means to 110 drive the successive rolls at a progressively increasing peripheral speed, substantially as described.
9. In a machine of the character described, the combination of a series of supply rolls carrying fabric of progressively 115 decreasing width, a series of sets of feed and pressure rolls arranged to receive adhering strips of fabric from the preceding rolls, and a superposed strip of fabric from 120 a supply spool, and means to drive the successive rolls at a progressively increasing peripheral speed, substantially as described.
10. In a machine of the character described, the combination of a series of supply rolls carrying fabric, a series of sets 125 of feed and pressure rolls arranged to receive adhering strips of fabric from the preceding rolls, and a superposed strip of fabric from 130 a supply spool, and means to drive the successive rolls at a progressively increasing peripheral speed, substantially as described.

a supply roll, means to guide the adhering strip of fabric between the pressure rolls, and independent means to guide the superposed strip of fabric with relation to the 5 adhering strips.

10. In a machine of the character described, the combination of a series of supply spools carrying fabric, and a series of sets of feed and pressure rolls arranged to 10 receive adhering strips of fabric from the preceding rolls and a superposed strip of fabric from a supply spool, means to drive the rolls, and means to reverse the direction of rotation of the rolls, substantially as described.

11. In a machine of the character described, the combination of a series of supply spools carrying fabric, a series of sets of feed and pressure rolls arranged to receive 20 adhering strips of fabric from the preceding rolls and a superposed strip of fabric from a supply roll, and a take-up drum having a grooved periphery of less width than the flap whereby to cup the latter, and means to drive the feed rolls and drum simultaneously, and a clutch interposed in the driving mechanism whereby to enable the drum to be driven independently of the rolls, substantially as described.

30. 12. In a machine of the character described, the combination of a source of stock supply of a determined width, a cupping roll narrower than the stock, and means to wind up the stock on said cupping roll.

35. 13. In a machine of the character described, the combination of a source of stock supply of a determined width, a cupping roll narrower than the stock, a guide to direct the stock onto the cupping roll and 40 means to wind up the stock on said cupping roll.

14. In a machine of the character described, the combination of means for making laminated flap stock, a take-up and 45 shaping roll having a channel, the sides of which are spaced apart less than the width of the flap, and means to wind up the flap stock on the take-up roll.

15. In a machine of the character described, the combination of means for making 50 laminated flap stock, a take-up and shaping roll having a channel, the sides of which are spaced apart less than the width of the flap and the bottom of which is concaved, and means to wind up the flap stock 55 on a take-up roll.

16. In a machine of the character described, the combination of means for making laminated flap stock, a take-up and 60 shaping roll having a channel, the sides of which are spaced apart less than the width of the flap, and means to wind up the flap stock under tension on the take-up roll.

17. In a machine of the character described, the combination of means for making laminated flap stock, a take-up and 65 shaping roll having a channel, the sides of which are spaced apart less than the width of the flap and the bottom of which is concaved, and means to wind up the flap stock 70 under tension on the take-up roll.

18. In a machine of the character described, the combination of means for making laminated flap stock, a take-up and 75 shaping roll having a channel, the sides of which are spaced apart less than the width of the flap, a guide to direct the stock onto the take-up roll, and means to wind up the flap stock under tension on the take-up roll.

19. In a machine of the character described, the combination of means for making laminated flap stock, a take-up and 80 shaping roll having a channel, the sides of which are spaced apart less than the width of the flap and the bottom of which is concaved, a guide to direct the stock onto the 85 take-up roll, and means to wind up the flap stock under tension on the take-up roll.

In testimony whereof I have hereunto signed my name in the presence of two witnesses.

WILLIAM C. STEVENS.
